UNITED STATES PATENT OFFICE.

WILLIAM CLARK, OF BOSTON, MASSACHUSETTS.

IMPROVED REGULATOR FOR GAS-BURNERS.

Specification forming part of Letters Patent No. 57,087, dated August 14, 1866.

To all whom it may concern:

Be it known that I, WILLIAM CLARK, of Boston, in the county of Suffolk and State of Massachusetts, have invented an Improvement in the detail of the construction of Gas-Burners; and I do hereby declare that the following, taken in connection with the drawings which accompany and form part of this specification, is a description of my invention sufficient to enable those skilled in the art to practice it.

This invention relates to the improvement of the devices which are frequently introduced into gas-burners near the orifice therein at which the gas escapes and close to which it is burned, between said orifice and the cock by which the supply of gas is admitted to or is shut off from the burner.

This device, usually termed a "regulator," has for its object the control of the flow of the gas-current and the reduction of its pressure by "wire-drawing" it, so termed, through small apertures, and by lessening the momentum of the current.

This invention consists in such a regulating device, so constructed and arranged that while it is capable of adjustment to increase or diminish the area of the opening for the flow of the gas-current, it shall discharge the gas within the burner toward its longitudinal axis, and so that the particles of gas, in their impingement against each other at or near said axis, shall thereby have their momentum lessened, and shall proceed to the escaping-orifice from the burner in the line of the axis thereof as the resultant line of motion produced by the form given to the regulator-passage and the impingement against each other of the particles projected therefrom.

Of the drawings, A denotes a gas-burner embodying my invention, and having a lower portion thereof removed, so as to illustrate the interior construction. B shows, in plan, the lower part of the burner with the tip end removed. Within this lower part, a, is formed a valve-seat, which the frusto-conical valve b fits closely on its inclined surface, the diameter

of the large end of valve b being smaller than the internal diameter of a, so that when the conical surface of the valve b is not in contact with its seat a current of gas can pass the valve.

The piece a is provided with a central cross-bar, c, in which are cut the screw-threads of a nut fitting the screw-threads formed on the stem d of the valve, so that by turning the valve it is adjusted toward or from its seat, diminishing or increasing the size of the opening through which the gas passes on its way to be burned.

The gas passing in the annular conical space between the valve b and its conical seat is directed thereby toward the apex of the cone of which the valve b is the frustum, and the particles of gas meeting at that point, having their momentum diminished by their impact against each other and their direction of motion changed thereby, proceed to escape from the orifice in the tip e.

Practical experiments have proved to me that a current of gas directed toward the burning-orifice by and through an inclined annular passage produces a thinner and better-shaped flame than will any other form of regulator in connection with the same tip, and that a perceptible gain in the amount of light produced from the consumption of a given quantity of gas is thereby obtained.

The pin f in the end of the valve-spindle d serves to prevent accidental loss of the valve b, and also acts as a handle by which the valve is easily turned, and as an index by which to observe the number of turns or the fraction of a turn given to the valve.

I claim—

In combination with the tip of a gas-burner, a regulating device constructed of the frusto-conical valve and valve-seat, with the cross-bar c and the screw-spindle d, operating together in the manner described.

WM. CLARK.
